(57) **CLAIM**

The ornamental design for an earphone, as shown and described.

DESCRIPTION

FIG. 1 is a front, top perspective view of an earphone showing my new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partially enlarged view of FIG. 1 thereof; and,
FIG. 10 is a partially enlarged view of FIG. 3.

The broken lines shown on the drawings depict portions of the earphone that form no part of the claimed design. The dot dash broken lines surrounding portions of the earphone in FIGS. 1 and 3 and illustrated in the enlarged views of FIGS. 9 and 10 form no part of the claimed design.
